UNITED STATES PATENT OFFICE.

DUNCAN C. HOOKER, OF FARMINGTON, CONNECTICUT, ASSIGNOR TO THE JOHNS-PRATT COMPANY, OF HARTFORD, CONNECTICUT, A CORPORATION OF CONNECTICUT.

INDICATING MEANS FOR INCLOSED FUSES.

1,087,120.

Specification of Letters Patent.

Patented Feb. 17, 1914.

Application filed February 7, 1913. Serial No. 746,808.

To all whom it may concern:

Be it known that I, DUNCAN C. HOOKER, a citizen of the United States, residing at Farmington, in the county of Hartford and 5 State of Connecticut, have invented a new and useful Improvement in Indicating Means for Inclosed Fuses, of which the following is a specification.

This invention relates to the provision of 10 indicating means for inclosed electric fuses of small capacity.

Hitherto it has been considered impracticable to provide an inclosed fuse of small capacity, for instance two amperes and below, with means for indicating whether or not the fuse is good or blown. The fusible element of such a small fuse is necessarily so slight that its mechanical strength is not sufficient to restrain a spring or tension device, such as is employed with any of the 20 mechanical indicators at present in use; the disruption of such a small fusible element is accompanied by so little violence that it is insufficient to operate any indicator depending upon pressure; and the resistance of such a fine fusible element is too high and its conductivity too low to permit the use of a shunt wire indicator, similar to that commonly applied to inclosed fuses 25 of greater capacities. When two conductors are in parallel, the amount of current carried by each will be inversely proportionate to their resistances. It is evident therefore that if the main fusible element is made small enough to constitute a properly calibrated fuse of two amperes' capacity or below, the conductivity of the indicator wire will be so large in proportion that its share 30 of the total current carried by the two will be sufficient to cause it to heat to a point where the indicator spot will ignite or discolor, even though the main fusible element is not blown. Another reason for the impracticability of a shunt circuit indicator 35 for such a small fuse is that the indicator wire itself is capable of carrying so much current that no matter how small the conductors, the device would carry more current than its rating permits.

40 The object of this invention is to overcome the difficulties mentioned and provide a practical indicator for a fuse of small capacity.

Referring to the accompanying drawings, 45 Figure 1 shows a side view of an inclosed

fuse provided with an indicator which embodies this invention, the indicating label being omitted from this view. Fig. 2 shows a longitudinal section of the same taken through the indicator and label.

60

A common type of inclosed fuse is illustrated. This fuse has a tubular inclosing case 1 of fiber or other suitable insulating material. The ends of this tubular casing are usually closed by brass terminal caps 2. 65 Extending inwardly and in contact with these conducting end caps are the internal terminals 3 ordinarily formed of copper wire. These interior terminals are joined by the fusible wire or strip 4. The casing 70 may or may not be filled with the commonly employed granular non-conducting material.

The indicating wires 5 may have their ends connected with the conducting terminals in any desired manner. The drawings show the ends of these wires as electrically connected with the end caps by means of metallic eyelets 6. In the construction illustrated the indicator wires extend inside of 75 the casing for a distance from the end caps and near the middle pass through holes to the exterior. The outer ends of these indicator wires are not electrically connected with each other. The end of one is shown 80 as bent down against the outer surface of the tubular casing and the end of the other is similarly bent in such manner that the two ends cross or overlap, without however, making electrical contact with each other. 85 An insulating sheet 7, of paper or other suitable non-conducting or high resistance material is inserted between the ends of the two wires and then over this may be placed a label 8 provided on the inside with a spot 90 of fulminating paste or other readily inflammable material. When a fuse constructed in this manner is placed in an electrical circuit so as to form a part thereof, all the current will pass through the fusible 95 element—the wire or strip 4—and none through the indicator wires, as the ends of the indicator wires are separated by material having too great resistance. The indicator wires, however, are alive as their ends 100 are connected with the conducting terminals. As long as the fusible element remains intact the insulating sheet of paper or other substance between the ends of the indicator wires will be subjected to no electrical stress 105

110

except the drop of potential between the terminals resulting from the resistance of the fuse proper and its terminals.

When the fusible element is disrupted by excess current flow, or in other words when the fuse is blown, the insulating sheet between the ends of the indicator wires is subjected to the full potential of the circuit in which the fuse is installed, as one of the terminals will be alive and the other dead. The stress of this line voltage is sufficient to break down or puncture the insulation or overcome the resistance and thereby effect an electrical connection between the ends of the indicator wires. These wires will then rapidly heat and burn off causing the indicator spot to ignite or discolor and show a black spot on the label which will indicate that the fuse has been blown. The electrical connection formed between the overlapped ends of the indicator wires when the main fuse is blown is accompanied by a very slight arcing at the point of their intersection and the resulting heat can be utilized to indicate the blowing of the fuse in any of the well known ways employed for this purpose with the larger sizes of fuses. The sheet of paper which is desirably used has sufficient dielectric strength to resist a drop of potential caused by the resistance of the fusible element but is insufficient to resist the potential of the line after the fusible element is disrupted, or resist the surge or kick of the current at the time the fuse opens. Other material than thin paper may be employed for this purpose if desired, such for instance as a sheet or piece of material that would commonly be classed as a conductor but which has a resistance so high that it would prevent any appreciable flow of current when subjected only to the potential due to the

drop across the fusible element, yet would permit enough current to flow when subjected to the full potential of the line to cause the operation of the indicator.

45

The invention is not limited to any specific form of indication which might be brought about by the operation of the indicator wires, or to the particular arrangement of insulating sheet which separates the free ends of the indicating wires, or to the specific construction of the casing or conducting terminals illustrated in the drawings.

The invention claimed is:

1. An inclosed fuse having a fusible conductor, a sectional indicating conductor with the ends of the sections crossed on the exterior of the fuse, and a sheet of paper of dielectric strength sufficient to resist a drop of potential caused by the resistance of the fusible element, but insufficient to resist the potential of the circuit after the fuse is disrupted, inserted between the crossed ends of the sections of the indicating conductor.

2. An inclosed fuse having a fusible conductor, a sectional indicating conductor with the ends of the sections crossed on the exterior of the fuse, a sheet of paper of dielectric strength sufficient to resist a drop of potential caused by the resistance of the fusible element, but insufficient to resist the potential of the circuit after the fuse is disrupted, inserted between the crossed ends of the sections of the indicating conductor, fulminate applied to the exterior of the fuse adjacent to the crossed ends of the indicating conductor, and a label covering the fulminate.
